UNITED STATES PATENT OFFICE.

WILLIAM C. ZESS, OF BETHESDA, MARYLAND.

DIVER'S SANDAL.

1,383,049.

Specification of Letters Patent. Patented June 28, 1921.

Application filed October 7, 1920. Serial No. 415,244.

To all whom it may concern:

Be it known that I, WILLIAM C. ZESS, a citizen of the United States, and a resident of Bethesda, in the county of Montgomery 5 and State of Maryland, have invented certain new and useful Improvements in Divers' Sandals, of which the following is a specification.

My present invention relates generally to 10 diver's footgear, and more particularly to a diver's weighted sandal to be worn over a gum or similar boot so that during periods between diving operations, the diver may slip off the sandals and walk in the boots 15 without undue wear of the foot portions of his suit and without the necessity of having slippers and the like handy for this purpose.

It is a well known fact that divers' sandals 20 are commonly formed of cast iron and that while this construction suffices on sand or mud bottoms, it is extremely dangerous on rock bottoms because of the likelihood of slipping, and it is also true that when manufactured of cast iron with walls and base of sufficient thickness to prevent danger of breaking, the total weight so closely approaching the maximum weight capable of effective use, as to preclude the addition of 25 a material such as lead for the purpose of added traction on rock.

It is furthermore of common knowledge to provide lead soles for divers' shoes or sandals the uppers of which are formed of 35 leather and the soles of which are usually attached by wooden inner soles. Such shoes or sandals lack the desired durability, which means safety to the diver, the leather uppers quickly rot in salt water and the 40 wooden inner soles crack and split.

It is therefore the primary object of my present invention to provide a sandal having all of the durable qualities of cast iron, of a nondeteriorating material which will at 45 the same time admit of a lead sole and still come within the weight limit, as well as a novel construction and arrangement of parts adapting the same to practically a life time use and equal effectiveness and safety on 50 sand, mud and rock bottoms.

Sandals at present formed of cast iron are also provided with toe caps into which the forward portions of the side walls merge, and which caps stand up above the foot to 55 such an extent as to materially interfere with movement of the diver's feet in ascend-

ing and descending ladders and constantly present a decided danger of fouling the lines. A further object of my invention is to avoid this danger by the provision of a sandal 60 having a close fitting toe cap and having sufficiently low side walls and a sufficiently low heel counter as to permit the sandal to be readily fitted and removed.

In the accompanying drawing illustrating 65 my invention, and forming a part of this specification—

Figure 1 is a perspective view illustrating the practical application of a sandal constructed in accordance with my invention, 70

Fig. 2 is a central longitudinal section through the sandal, and

Fig. 3 is a partial bottom plan view of the sandal.

Referring now to these figures and particularly to Fig. 1 I have shown a portion of one leg of a diver's suit at 10, whose usual lower foot portion is inclosed by a gum boot or overshoe 11 to be in turn extended within the sandal 12 as shown. The gum 80 boot or overshoe 11 permits the diver to walk around upon shipboard by simply slipping off the sandal, during the not infrequent intervals between diving operations whose duration is such that the diver removes only the heavier portions of his gear, that is breast plate, helmet and sandals and still retains his suit, the foot portions of which the boot or overshoes protect from undue wear.

The body or upper of my improved sandal I cast of manganese bronze which I have found to be fully equal in lasting qualities both as regards breakage and the action of salt water, to cast iron, and which has the 90 advantage over cast iron that the body or upper of the sandal when fully formed with walls and base of a desired thickness still permits of the use of the lead sole 13 of substantial depth or thickness required for durability and adherence, and comes within the weight limit which is around eighteen pounds for each sandal.

The upper portion of the sandal has a toe cap 14, into which the forward ends of its 105 side walls 15 merge in gradually curving relation and which toe cap is so formed as to closely fit the upper forward portion of the boot or overshoe 11, the relatively low side walls 15 and the heel counter 16 into which 110 the rear ends of the side walls merge, permitting the sandal to be readily fitted on

and removed from the boot or overshoe. Thus in spite of the close fitting toe cap, which is depressed materially below that of the usual sandal in order to avoid danger existing in the present sandals in catching in ladder rungs and fouling lines, I obtain the advantages of this construction without any disadvantages.

The upper or body portion of the sandal 10 is furthermore cast with a continuous depending flange or rib 17 around the edge of its flat base 18, this rib extending beyond the base for the full depth of the proposed lead sole 13 so that its lower surface comes 15 substantially flush with the lower surface of the lead sole in order to protect the latter from lumping up on the base of the shoe when the toe or heel is stubbed against solid articles for instance rock.

20 The extension of the flange or rib below the base of the upper also forms a space within the flange so that the lead sole may be conveniently finished by simply throwing molten lead into this space to the level 25 of the edge of the rib or flange. Prior to this however the base 18 of the upper or body of the sandal is tapped at a plurality of points and threaded bolts 18^a are threaded into the tapped openings with their heads 30 projecting into the space inclosed by the flange or rib 17 so that these heads will be subsequently embedded in the lead sole 13 and will operate to securely hold the latter in place upon the base 18 within the rib or 35 flange 17.

The extreme lower or tractive surface of the sandal will thus be flat as usual adapting the sandal to effective use upon sand or mud bottoms, while the presence of the lead 40 sole 13 also lends effective traction in the use of the sandal upon rock bottoms where in the absence of the lead or comparatively soft surface constant danger of slipping is present.

45 The lead sole connected as it is to the upper or body of the sandal, and protected as

it is by the rib or flange 17, is well adapted to last practically the life time of the upper or body of the sandal and is, like the material of which I form the upper or body for 50 the purpose of permitting the addition of the lead sole, uninfluenced by the deteriorating influence salt water has upon leather, wood and similar materials previously used.

The means utilized for attaching the sandal and which may of course necessitate renewal from time to time, I have shown in the form of a loop 19 riveted or otherwise secured to the heel counter of the body, for the movable or running engagement of a 60 strap 20 which is buckled around the boot or overshoe 11 above the instep. It is to be understood however that other means may be utilized for this purpose although those proposed are obviously efficient from the 65 standpoint of ready connection and detachment.

I claim:

1. A diver's sandal comprising a body or upper having a base and a depending rib or 70 flange around the edge of the base, and a lead sole secured to the base within the rib or flange.

2. A diver's sandal comprising an upper or body formed of manganese bronze and a 75 lead sole, the upper or body having a depending protecting flange or rib around the edge of the sole.

3. A diver's sandal including an upper having a base, a lead sole applied directly to 80 the base, and attaching members secured to the base and embedded in the lead sole, said upper having means to protect the surrounding edge of the lead sole as described.

4. A diver's sandal comprising a manganese bronze upper having a base and a depending flange or rib around the base, a lead sole on the base within and flush with the said rib or flange, and bolts threaded into the base, having their heads embedded in 90 the lead sole as described.

WILLIAM C. ZESS.
